NEEDLE CYLINDER FOR SINKER-TYPE CIRCULAR KNITTING MACHINES

Benjamin Fried, 2197 Cruger Ave., Bronx, N.Y.

Filed Feb. 14, 1958, Ser. No. 715,297

7 Claims. (Cl. 66—115)

The present invention relates to circular knitting machines of the general type including a sinker top needle cylinder carrying axially reciprocating needles and radially reciprocating sinkers, and more particularly to improvements in the sinker mounting.

In operating knitting machines of the above type, tubular knitted goods are manufactured by the cooperating reciprocating movement of the needles and the sinkers, the needles being mounted in the needle cylinder or on its periphery for up-and-down movement while the sinkers ride on the upper rim of the cylinder and move back-and-forth in a radial direction. The needles and sinkers are arranged in interdigitating relationship so that their reciprocating movements knit the threads into a fabric, as is well known per se. This operation of knitting machines is entirely conventional. As experience has shown, it causes considerable collection of sludge or lint at or near the rim of the needle cylinder where the sinkers and needles cooperate to knit the threads into a fabric.

The accumulation of sludge or lint is particularly bothersome in the conventional guide slots for the inner ends of the sinkers and in pockets formed between these guide slots and the needles moving on the periphery of the needle cylinder. This accumulation of dirt is especially pronounced in fine-gage knitting machines using as many as 32-34 sinkers per inch. It appears to a smaller or larger degree in all machines and regardless of the thread material, being most strongly noticeable in the knitting of wool and some of the more recently developed synthetic fibers, such as Orlon, Acrilan and others.

When dirt accumulates in the sinker guide slots, the collected dirt will tilt the sinkers out of their horizontal position on the cylinder rim, causing vertical unevenness in the knitted pattern and other operation troubles. When dirt clogs the pockets between the sinker guide slots and the needles, it eventually begins to bend the needles outwardly so that their proper horizontal position and predetermined relationship to the sinkers is disturbed. This will obviously result in similar operational difficulties. Accordingly, the needle cylinder must be frequently disassembled and cleaned to avoid a breakdown in the knitting operation. This is a time-consuming task since it requires removal of all sinkers and needles from the cylinder. Clearly, this procedure considerably increases the manufacturing cost and, accordingly, many attempts have been made to provide means for cleaning needle cylinders.

It is the principal object of my invention to provide a self-cleaning sinker-type needle cylinder so as to eliminate accumulation of sludge or lint in the sinker guide slots and in the pockets between the guide slots and the needles.

It is a concomitant object of this invention to provide an easily and economically hardenable riding ledge for the sinkers.

2

Other objects and advantages of the invention will become clear from the following detailed description of certain preferred embodiments thereof, taken in conjunction with the accompanying drawing wherein

- 5 Fig. 1 is a perspective view of a sinker mounting according to one embodiment of the invention;
Fig. 2 is a section along line II—II of Fig. 1;
Fig. 3 is a vertical section of the upper portion of a knitting cylinder showing another embodiment of the 10 sinker mounting; and
Fig. 4 is a sectional view similar to Fig. 2 but showing yet another embodiment of the sinker mounting.
Conventional portions of the needle cylinder, including all of the needle mounting and the sinker mounting except for the positioning of the sinker guide slots, may take any desired form and are accordingly either not shown at all or shown diagrammatically to facilitate the clear understanding of the structure of the invention proper.
- 20 In accordance with the present invention, there is provided a needle cylinder for a circular knitting machine, wherein the radial sinker guide slots holding the inner ends of the sinkers are spaced from the cylinder so that lint or sludge produced during knitting may be automatically eliminated by falling through the slots and the space between the slots and the cylinder. Preferably, the guide slots for the inner ends of the sinkers are spaced inwardly from the needle cylinder.

Referring now more particularly to Figs. 1 and 2, there 30 is shown a needle cylinder body 10 with an upper ledge 11 on which the sinkers 12 ride. As is well known in the knitting machine art, the sinkers are mounted on slotted sinker dial 13, the radially arranged slots 14 in the dial holding the respective sinkers for radial reciprocating movement therein. A conventional annular sinker cap 15 is mounted over the outer ends of the sinkers. All of this structure is conventional, as is the needle mounting which is not shown in these figures to clarify the illustration of the invention.

40 In contrast to conventional needle cylinders whose ledge 11 was slotted to receive the sinkers, my ledge 11 has a smooth riding surface and the inner ends of the sinkers 12 are held in position by guide slots 16 which are inwardly spaced from the cylinder body 10, leaving a space 17 between the cylinder body and the guide slots. Obviously, when the sinkers 12 are radially reciprocated in their guide slots, any lint, sludge or dirt produced during knitting will drop through the slots and space 17.

The structure of the support for the sinker guide slots 50 may take any suitable form and those shown are merely given by way of example. As illustrated in Figs. 1 and 2, the guide slots are machined into an arcuate metal ring 18 which is welded or otherwise fixed to support ring 19. The slotted ring may be screwed on or otherwise fixed to its support. The slotted support ring is bolted to the needle cylinder at 20, 20. Any suitable mounting may, of course, be used. Also, instead of providing a slotted ring 18, individual arcuate metal blades could be welded to the support ring 19, such blades being spaced 60 so as to receive a corresponding sinker between two adjacent blades. In this arrangement, pairs of adjacently mounted blades would form the guide slots 16. Other slotted structures may be devised by the machinist after he benefits from the essential teaching of the present invention, requiring the spacing of the sinker guide slots from the needle cylinder.

A preferred embodiment of the sinker guide slot mounting according to my invention is illustrated in Fig. 3. The top portion of the circular knitting machine shown in this figure includes the conventional needle cylinder 100 with its sinker dial 103 and sinker cap 105, sinkers 102

being mounted in radial slots 104 in the sinker dial and held in position by the sinker cap. The needle cylinder is provided with longitudinally arranged grooves 111 holding needles 112 which are axially slideable in grooves 111 in a manner known per se. The identical needle mounting may be used in the needle cylinder of Fig. 1 where it has been eliminated to clarify the showing.

The difference between the embodiments of Figs. 1 and 3 lies in the specific configuration of the sinker guide slots. While the guide slots are inwardly spaced from the needle cylinder in both embodiments, the slot support ring 19 is relatively close to the needle cylinder in the embodiment of Fig. 1. In the embodiment of Fig. 3, on the other hand, sinker ring 109 is far removed from the needle cylinder and the guide slots 106 are of different shape. The sinker ring 107 is an integral member of L-shaped cross section and is attached to the needle cylinder by means of bolts 110. Slots 106 are machined into the horizontal flange portions of the sinker ring to provide the guide slots for the sinkers.

Fig. 4 schematically illustrates yet another embodiment of the invention, all conventional structures being identical with the circular knitting machine cylinder shown in Fig. 3. In this embodiment, the needle cylinder 200 is provided with a stepped top consisting of shoulder 211 and ledge 201 on which the sinkers 202 ride. Sinker ring 209 is bolted at 210 to the needle cylinder below chamber 207, the sinker ring being slotted at 206, similarly to the embodiment of Fig. 3. In the embodiment of Fig. 4, too, lint tending to collect in the sinker guide slots will simply drop into recessed chamber 207 and will be removed mostly through slot portions 206a into the open interior of the cylinder where it will fall on the floor or machine support base. Dirt accumulating in chamber 207 after operation of considerable duration can be removed by occasionally taking off ring 209 to clean the machine. Nevertheless, even this embodiment of the invention constitutes a considerable improvement over conventional needle cylinders, not only because of its substantial self-cleaning feature but also because it provides a smooth top ledge which can be readily tempered or hardened. Also, the packing of lint behind the needle will be avoided, at least for a substantial period of time, because most of the dirt will be removed through slot portions 206a and any accumulation chamber 207 will be very slow.

In addition to the self-cleaning feature common to all embodiments of the invention, it will be noted that the upper ledge of the needle cylinder, upon which the sinkers ride, is always a smooth metal ring which, therefore, constitutes no problem in hardening. It has been found that the slotted upper rims of conventional metal needle cylinders are very difficult to temper or cannot be satisfactorily hardened at all. Accordingly, the guide surfaces for the sinkers in the needle cylinders of the prior art are often relatively soft so that the rapidly reciprocating sinkers tend to bite into the cylinder, forming irregular grooves which cause further irregularities in the sinker movements. In contrast to this, the smooth metal ledges of the needle cylinders of the present invention can be tempered without difficulty, thus providing hard riding surfaces for the reciprocating sinkers.

While I have described the improved needle cylinder of my invention with reference to specific embodiments, it will be obvious that I am not concerned with any specific cylinder shape, needle mounting, sinker, sinker dial or sinker cap, nor with any specific slotted ring for guiding the inner ends of the sinkers, the only essential requirement being that the guide slots for the inner ends of the sinkers are spaced, preferably inwardly, from the cylinder body, leaving a space between the body and the guide slots. Many variations and modifications may occur to the skilled in the art within the framework of the stated requirement without departing from the spirit and

scope of this invention as defined in the appended claims.

What I claim is:

1. A needle cylinder for a circular knitting machine, comprising a substantially smooth upper ledge, a plurality of sinkers radially arranged and riding on said ledge with an inner portion of the sinkers extending inwardly from the ledge, and annular guide slot means defining a plurality of radially extending slots opening into the interior of the cylinder and guiding the inner portions of said sinkers, the guide slots being spaced and extending inwardly from said cylinder ledge and guide slot means and the cylinder adjacent the ledge defining an open space inwardly of the ledge.

2. The needle cylinder of claim 1, wherein said smooth upper ledge is of hardened metal to constitute a wear-resistant riding surface for the sinkers.

3. A needle cylinder for a circular knitting machine, comprising a substantially smooth upper ledge, a plurality of sinkers radially arranged and riding on said ledge with an inner portion of the sinkers extending inwardly from the ledge, and, an annular sinker guide member, defining a plurality of radially extending slots opening into the interior of the cylinder and guiding the inner portions of the sinkers, the sinker guide member being spaced vertically from said ledge and extending inwardly from the cylinder, a major part of said slots extending inwardly from said cylinder and said inwardly extending guide slot member and the cylinder forming an open space therebetween.

4. A needle cylinder for a circular knitting machine, comprising a substantially smooth upper ledge, a plurality of sinkers radially arranged and riding on said ledge with an inner portion of the sinkers extending inwardly from the ledge, a sinker guide ring spaced vertically from said ledge and having a plurality of radially extending slots opening into the interior of the cylinder and guiding the inner portions of the sinkers, and means for supporting the sinker guide ring on the cylinder in inwardly spaced, concentric relationship thereto, at least a major part of the guide slots extending inwardly from the cylinder, said sinker guide ring and the cylinder forming an open space therebetween.

5. The needle cylinder of claim 4, wherein said sinker guide ring comprises an outwardly flared upper portion provided with said radially extending slots and a solid support portion whereto said slotted upper portion is connected, said upper portion extending with its slots from the solid support portion substantially to the circumference of the cylinder but spaced upwardly from the cylinder ledge.

6. The needle cylinder of claim 4, wherein said sinker guide ring is of substantially L-shaped cross section having a solid cylindrical support portion and an upper slotted portion extending horizontally therefrom toward the cylinder but inwardly spaced therefrom.

7. A needle cylinder for a circular knitting machine, comprising a stepped top consisting of a smooth upper ledge and a shoulder, a plurality of sinkers arranged and riding on said ledge with an inner portion of the sinkers extending inwardly from the ledge, a sinker guide ring spaced vertically from the ledge and having a plurality of radially extending slots opening into the interior of the cylinder and guiding the inner portions of the sinkers, and means for supporting the sinker guide ring on the cylinder below said shoulder, at least a major part of the guide slots extending inwardly from said ledge toward said supporting means, said inwardly spaced guide slot parts, said shoulder and said ledge defining a recessed chamber.
